CLAIM

The ornamental design for a liquid disbursement mop, as shown and described.

DESCRIPTION

FIG. 1 is an isometric view of the mop of the present invention.

FIG. 2 is an isometric view of the present invention, showing cleaning head member rotation.

FIG. 3 is an isometric view of the present invention as the cleaning head member continues its rotation from the position shown in FIG. 2.

FIG. 4 is an isometric view of the presenting invention showing the cleaning head member rotated 180° from the position shown in FIG. 1.

FIG. 5 is a front view of the design of the present invention.

FIG. 6 is a rear view of the design of the present invention.

FIG. 7 is a top view of the design of the present invention.

FIG. 8 is a bottom view of the design of the present invention; and,

FIG. 9 is a side view of the design of the present invention. The portions shown broken away are done so to indicate an unspecified length.
